US0D1005804S

(12) **United States Design Patent** (10) Patent No.: **US D1,005,804 S**
(45) Date of Patent: ** Nov. 28, 2023

(54) **CONTAINER**

(71) Applicant: **b.box for kids developments Pty Ltd**,
Mulgrave (AU)

(72) Inventors: **Sylvain Jacques Amatoury**, Mulgrave
(AU); **Lisa Edlund Tjernberg**,
Mulgrave (AU)

(73) Assignee: **b.box for kids developments Pty Ltd**,
Notting Hill (AU)

(**) Term: **15 Years**

(21) Appl. No.: **29/820,286**

(22) Filed: **Dec. 21, 2021**

(51) LOC (14) Cl. **07-01**

(52) U.S. Cl.

USPC **D7/703**; D7/629

(58) **Field of Classification Search**
